US0D1054621S

(12) **United States Design Patent** (10) **Patent No.:** **US D1,054,621 S**
(45) **Date of Patent:** **** Dec. 17, 2024**

(54) **POLE STAND**

(71) Applicant: **Kelly Louden**, Redmond, OR (US)

(72) Inventor: **Kelly Louden**, Redmond, OR (US)

(73) Assignee: **Kelly Louden**, Redmond, OR (US)

(**) Term: **15 Years**

(21) Appl. No.: **29/753,732**

(22) Filed: **Oct. 1, 2020**

Related U.S. Application Data

(62) Division of application No. 29/611,784, filed on Jul. 25, 2017, now Pat. No. Des. 899,827.

(51) **LOC (14) Cl.** **26-05**

(52) **U.S. Cl.**

USPC **D26/138; D6/681**

(58) **Field of Classification Search**

USPC D6/672, 681, 681.1, 682, 682.3, 682.5, D6/512, 712; D11/166; D21/839, 811; D26/138, 167

CPC . F21V 21/06; F21V 21/10; F21S 8/085; F21S 4/10; F16M 11/24

See application file for complete search history.

(57) **CLAIM**

The ornamental design for a pole stand, as shown and described.

DESCRIPTION

FIG. 1 is a perspective view of a pole stand showing my new design;

FIG. 2 is a close up perspective view of the base portion;

FIG. 3 is a close up side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a perspective view of a second embodiment of the pole stand showing my new design;

FIG. 11 is close up perspective view of the base portion;

FIG. 12 is a close up side elevation view thereof;

FIG. 13 is a top plan view thereof;

FIG. 14 is a bottom plan view thereof;

FIG. 15 is a front elevation view thereof;

FIG. 16 is a rear elevation view thereof;

FIG. 17 is a left side elevation view thereof; and,

FIG. 18 is a right side elevation view thereof.

The broken lines depict portions of the pole stand in which the design is embodied that form no part of the claimed design.
